(57) **CLAIM**

The ornamental design for an L-base earplug dispenser, as shown and described.

DESCRIPTION

FIG. 1 is a front perspective view of an L-base earplug dispenser in accordance with the new design;

FIG. 2 is a front elevation view thereof;

FIG. 3 is a rear elevation view thereof;

FIG. 4 is a side elevation view thereof;

FIG. 5 is a side elevation view thereof, for the side opposite that of FIG. 4;

FIG. 6 is a top elevation view thereof;

FIG. 7 is a bottom elevation view thereof;

FIG. 8 is an exploded front left perspective view thereof, depicting the container portion removed from the base portion;

FIG. 9 is an exploded front right perspective view thereof, also depicting the container portion removed from the base portion; and,

FIG. 10 is an exploded front right perspective view depicting the components of the design disassembled.

The broken lines shown in the figures represent portions of the L-base earplug dispenser that form no part of the claimed design.
